[57] ABSTRACT

A synchronizing apparatus having a phase sensitive zero crossing detector fed to a voltage controlled integrator and a box car circuit that is also fed by the voltage controlled integrator. The output of a sweep controlled difference integrator fed by the box car circuit is summed with the box car circuit output and fed the voltage controlled integrator and a voltage controlled multivibrator, the output thereof being fed to the zero crossing detector.

FIG. 6-b

CLOCK SYNCHRONIZATION SYSTEM**BACKGROUND OF THE INVENTION**

This invention relates to detection systems, and more particularly to an apparatus for determining the frequency of a clock oscillator driving a shift register generator.

The use of noise-like signals with predictable correlation functions has produced a new family of highly secure communication systems. These systems generally obtain their noise-like, pseudo-random modulating signal from a linear shift register generator being driven by a clock oscillator. A hostile eavesdropping receiver must first determine the clock frequency from the received code sequence before signal identification can be made or a suitable jamming signal prepared.

The invention takes advantage of the fact that the code signal generated by the shift register generator can only change state (zero crossing) when a clock pulse occurs. Thus, by detecting the zero crossing of the input code it is possible to generate the synchronizing signal for an oscillator located near the clock frequency.

The clock synchronization units used in the past have several limitations which limited the usefulness in ferret and jamming applications. One limitation is the limited frequency locking range caused in part by the fixed output pulselwidth from the zero crossing detector. For very large frequency ranges, the fixed output pulselwidth reduces the amount of phase error that can be used without losing lock. Another limitation for some applications is the variation in the steady state phase error across the frequency band. Since lock break occurs only at 0° to 180° , the amount of phase jitter that causes a lock break varies across the band and is a maximum only at the center of the locking range.

SUMMARY OF THE INVENTION

The invention incorporates a phase sensitive zero crossing detector capable of producing a pulse at each zero crossing with a width that can vary from 0° to 180° and a sweep control difference integrator that expands the frequency locking range and reduces the steady state phase variation with frequency.

The use of the phase sensitive zero crossing detector simplifies the loop by eliminating the need for an extra phase detector or a second zero crossing detector. It also increases the usable region of phase error which is important when the desired frequency locking range is large. The sweep control difference integrator in addition to increasing the frequency locking range maintains a nearly constant steady state phase error regardless of the center frequency.

The amount of input phase jitter that can be tolerated without the loop losing lock is increased by the phase sensitive zero crossing detector because of the increased usable phase error. The sweep integrator can also increase the allowable phase jitter by maintaining a constant steady state phase error in the center of the usable phase region (90°).

It is therefore an object of the invention to provide an improved clock synchronization system.

It is another object to provide a clock synchronization system having an extended frequency locking range.

It is still another object to provide a clock synchronization system that eliminates the variation in steady state phase error.

It is still another object to provide a clock synchronization system that uses a phase sensitive zero crossing detector having a square wave clock source rather than a fixed pulselwidth source thereby requiring only one zero crossing detector in the loop.

These and other advantages, features and objects of the invention will become more apparent from the following description taken in connection with the illustrative embodiment in the accompanying drawings.

DESCRIPTION OF THE DRAWINGS

15 FIG. 1 shows a clock synchronization unit used in the prior art;

FIG. 2 is a block diagram showing an embodiment of the present invention;

20 FIG. 3a shows an expanded block diagram of the phase sensitive zero crossing detector shown in FIG. 2;

FIG. 3b shows associated typical waveforms used for explanation of FIG. 3a;

25 FIG. 4a is an expanded block diagram showing the voltage controlled integrator shown in FIG. 2;

FIG. 4b shows associated waveforms used for explanation of FIG. 4a;

FIG. 5a is an expanded block diagram of the sweep control circuit shown in FIG. 2;

30 FIG. 5b shows associated waveforms used for explanation of FIG. 5a; and

FIGS. 6a and 6b are circuit diagrams of that shown in FIG. 2.

DETAILED DESCRIPTION OF THE PREFERRED EMBODIMENT

35 A prior art clock synchronization unit as shown in the block diagram of FIG. 1 takes advantage of the fact that code signals generated by a shift register generator only change state when a clock pulse occurs. Thus, by detecting the zero crossing of the input code with detector 11 it is possible to generate a synchronizing signal for oscillator or square wave generator 13 located near the clock frequency. The signal is fed to zero crossing detector 15 and its output fed to phase detector 17 together with the output of zero crossing detector 15, the output of phase detector 17 being fed to integrator 19. A standard phase loop incorporating a low pass filter is not used because of the pulse dropouts and the related very low frequencies contained in the spectrum of a pseudo-random sequence. Box car 21 holds the last-known charges between pulses thus eliminating the effect of pulse dropouts making the unit nearly independent of the received number of zero crossing per second.

55 The block diagram of the improved clock synchronization unit as shown in FIG. 2 incorporates two major improvements. Phase sensitive zero crossing detector 23 is capable of producing pulses at each zero crossing with a width that can vary from 0° to 180° ; the output of detector 23 is fed to box car 29. Sweep control difference integrator 25 fed by sweep control 27 and box car circuit 29 expands the frequency locking range and reduces the steady state phase variations with frequency. Voltage control integrator 31 is also used to optimize the simple RC integrator's time constant with changes in the loop's center frequency. The output of the difference integrator 25 and box car 29 is summed

in summing circuit 33 through loop filter 34 and fed to multivibrator 35.

An expanded block diagram of the phase sensitive zero crossing detector and some associated typical waveforms are shown in FIGS. 3a and 3b. The circuit incorporates NAND gates 36-38, inverter 39, and flip-flop 40. The typical waveforms illustrate the output pulses that would be observed if the loop's voltage controlled multivibrator clock 35 was synchronized with the clock source used to generate the received code sequence. When the two clock sources are synchronized in frequency but out of phase, the output pulselwidth would be decreased by an amount proportional to the phase difference. Should the two clock sources be located at different frequencies then the output pulselwidth varies in accordance with the difference between the two clock frequencies. Since the zero crossing detector employs a square-wave clock source rather than a fixed pulselwidth source, only one zero crossing detector is required in the loop.

The phase sensitive zero crossing detector of FIG. 3a serves two functions. First, it generates an output pulse at each zero crossing of the input code sequence. Secondly, it serves as a phase detector in that the pulselwidth of the generated zero crossing pulses is proportional to the phase difference between the system clock source and that used to generate the code sequence. The waveforms shown in FIG. 3b are for the case when the system clock has achieved perfect synchronization with the frequency of the shift register generator's clock source. As a result the zero-crossings (waveform Z) of the input code sequence (waveform A) are shown to have a pulselwidth equal to that of clock source (waveforms B and E). Should the system clock source (waveforms B and E) begin drifting in time or phase with respect to the code sequence the pulselwidth of the zero crossings (waveform Z) will decrease. If the phase drifting is continuous then a frequency difference exists between the two clock sources. A frequency difference will cause the zero crossing pulselwidths to decrease and then increase at a rate proportional to the difference between the two source frequencies. Waveform A represents the input code sequence. Waveform B is the system clock source which would be identical.

An expanded block diagram showing the voltage controlled integrator box car filter and associated waveforms are shown in FIGS. 4a and 4b. Two saturated NAND gates 41 and 42 are used to provide the proper amount of pulse delay to insure discharge of the box car before the arrival of the succeeding integrated pulse.

The expanded block diagram of the sweep control

circuitry and the associated waveforms are shown in FIGS. 5a and 5b. When a command is sent to the sweep control inputs, the voltage being sent to the integrator changes from B+ to a selected voltage, e_t . If a signal e_s is not present the integrator remains negatively saturated. If a signal is present, the output from the boxcar e_s , before synchronization, will exceed the threshold voltage e_t and the integrator will begin to integrate toward positive saturation. When the difference between the clock frequencies falls within the loop's bandwidth (locking range), the loop's voltage controlled multivibrator will lock itself to the clock used to generate the received code. The steady state phase error will adjust itself to the value required to make e_s equal to e_t . At this point the loop is completely locked and the integrator stops integrating and holds the voltage required to maintain the voltage controlled multivibrator at the proper center frequency.

The loop, in the locked mode, can follow clock variations as wide and as fast as the loop's bandwidth regardless of the clock's center frequency. The difference integrator provides the loop with a drift frequency tracking range limited only by the voltage controlled multivibrator and power supply voltage.

FIGS. 6a and 6b are circuit diagrams. Transistors designated as 51 can be type 2N2501 and those designated as 53 can be type 2N918. Diodes designated as 55 can be type 1N914 and those designated as 57 can be type 1N486B.

What is claimed is:

1. An apparatus for synchronizing a pseudo-random code comprising:
  - a. phase sensitive zero crossing detection means fed by the code;
  - b. a voltage control integrator fed by the zero crossing detecting means;
  - c. a box car circuit fed by the integrator and zero crossing detecting means;
  - d. a sweep control means;
  - e. a difference integrator fed by the sweep control means and the box car circuit;
  - f. a summing circuit fed by the difference integrator and the box car circuit an output of the summing circuit being fed to the voltage control integrator; and
  - g. a voltage control multivibrator fed by the summing circuit with the output of the multivibrator fed to the zero crossing detector.

2. An apparatus for synchronizing a pseudorandom code according to claim 1 wherein the output of said multivibrator is a square wave clock signal.
